DRESS GLOVE STRUCTURE

Paul A. Chanut, Paris, France

Application April 8, 1932, Serial No. 604,110

2 Claims. (Cl. 2—169)

The present invention relates to hand covers or gloves and more specifically to dress gloves, its primary object being to provide, as a new article of manufacture, a dress glove of novel structure, pattern and appearance characterized by the combination of a back element made of woven fabric and a palm element made of tanned skin or hide, the digit portion connecting tapes or fourchettes being also made of tanned skin or hide, both faces of the glove being thus of handsomely differentiated aspects.

A further object of the invention is to provide a dress glove of the aforesaid description having a very smart and close fit, devoid of bagginess and possessing great wearing life, these results being due to a novel shape or outline given to the several parts of which the glove is made up, great resistance to tear being imparted to the glove at the points of connection of said parts due to a novel way of uniting those parts that are exposed to heavy tractional or stretching stresses incidental to wearing by overcasting or whip-stitching their adjoined edges, while the edges of the other parts that are not exposed to the same heavy stresses are united together by ordinary lines of stitches i. e., by lap-stitching, for the sake of smartness.

With these and such other objects in view as will incidentally appear hereafter, the invention consists in the construction, combination and details of means that will be more fully described with reference to the accompanying sheet of drawing wherein is shown an illustrative embodiment of the same, it being understood that modifications, variations and adaptations may be resorted to within the scope and spirit of the invention as it is more directly claimed hereinafter.

In the drawing:

Figure 1 is a plan view of the main blank or back element of the glove, which includes a flaring forearm portion, a hand back portion and four digit portions, this main blank being in one piece and made of any suitable woven fabric.

Figure 2 is a plan view of the thumb upper cover, also made of a woven fabric advantageously matching that of the main blank, this view showing the peripheral or marginal hem-like flange of this thumb cover.

Figure 3 is a plan view of the palm blank or element of the glove, which includes a hand palm portion and four digit portions, this palm blank being in one piece and made of any suitable tanned skin or hide.

Figure 4 is a plan view of the thumb lower cover, also made of tanned skin or hide advantageously

matching that of the palm blank, this view showing a slanting or incurved cut separating the lower cover for the thumb proper from the lower cover for the ball of the thumb.

Figures 5 to 11 inclusive are plan views showing strips adapted to constitute the forearm base edge tapes and the digit connecting tapes or fourchettes, all of these tapes being intended according to the invention to be made of tanned skin, advantageously matching that of the palm blank.

Figure 12 is a diagrammatic edge view illustrating the mode of attachment by lap-stitching of the root edge of the palm blank to the corresponding edge of main blank.

Figure 13 is a diagrammatic edge view similar to Figure 12 but illustrating, by way of example, the mode of attachment by overcasting or whip-stitching their adjoined edges of the upper and lower covers or blanks of the thumb element over a portion of their peripheries.

Like reference numerals designate like parts throughout the several views.

The several blanks of which the improved glove according to the invention is made up are cut from suitable dies or patterns of known form of any appropriate size.

The main blank shown in Figure 1 is made of any convenient woven fabric such for example as linen, cloth, canvas, buckram, velvet, twill, etc. depending on the use ascribed to the glove, it being understood however that the invention is chiefly concerned with dress gloves. The choice of the texture and color or shade of the woven fabric of which the main blank is made depends largely on fashion requirements.

The main blank made of woven fabric represented laid on the flat in Figure 1 comprises a body 1 having side edges converging towards the digit or finger portions to provide, when the glove is fully assembled, a flaring forearm portion which gives the glove a musketeer gauntlet shape.

The body 1 of the main blank is limited by a rectilinear base edge 1^a and comprises a side flap 2 having a pointed tongue 3 beyond which is formed a V-shaped depression 4. Beyond this depression are in turn formed four digit or finger portions 5, 6, 7, 8 of suitable respective lengths.

The upper or back portion 9 for the thumb has the shape shown in Figure 2 when laid on the flat i. e. before assembly. The peripheral edge of this thumb upper cover 9 is flanged or hemmed at 9^a to permit easier assembly with the corresponding part of the body 1 of the main blank.

and with the edge of the thumb lower cover, as will be described hereafter.

The palm blank shown in Figure 3 is made of any suitable tanned skin or hide such for instance as fine leather or kid, which tanned skin or hide may have either a polished and bright surface or an unpolished and dull surface. The color or shade of this palm blank may be advantageously the same as that of the main blank, for example black, tan or putty-color, although naturally the colors of the two principal blanks adapted to constitute the hand back portion and the palm portion of the glove structure once it is assembled may be differentiated or otherwise harmonized to suit fashion or style requirements.

The palm blank comprises a body 10 having a pointed projection 11 extending in the direction opposite to that of its digit portions, designated by 14, 15, 16 and 17. Aligned or substantially aligned with the index digit portion 14 is an oppositely extending pointed flap 12 separated from the palm body 10 by an arcuate cut 13 flared outwardly at 13a.

The lower or palm cover for the thumb as shown in Figure 4 is made of the same tanned skin or hide as the palm blank shown in Figure 3 and it comprises a tip portion 18 separated from a bulging portion 20 adapted to cover the ball of the user's thumb by a slit 19, the extremity of the bulging portion 20 being pointed at 21.

The overall contour of the hand back portion and digit portions of the back element made of woven fabric is slightly larger than the overall contour of the skin palm element so that a hem-like flange 1b may be stitched (as shown by way of example in Fig. 13) on the peripheral edge of the main blank for overcasting or whip-stitching to the palm element and to the outer edge of the thumb upper cover 9.

The connection between the adjoined parts of the outline edges of the back and palm portions and of the thumb upper and lower covers is performed by whip-stitching which gives great resistance to heavy tractional or stretching stresses. This mode of attachment is illustrated diagrammatically by way of example in Figure 13 in connection with the thumb upper and lower covers.

The connection between the digit connecting tapes shown in Figures 7 to 11 and the palm portion and between the edge of the V-shaped depression 4 of the forearm portion of the main blank and the edge of the pointed projection 11 of the palm portion is effected by lap-stitching as shown diagrammatically in Figure 12. The connection between the thumb lower cover at 20 and the hand palm portion at 12 is also effected by lap-stitching.

The tapes 22-22', 24-24', 26-26', 28 and 29 all made of tanned skin are formed with middle folds 23, 25, 27 where required and with arcuate notches 24'', 28'', 29'' for fitting better between the digit portions 5, 6, 7, 8 and 14, 15, 16, 17. All these tapes are secured by lap-stitching as they undergo small stresses only.

The tapes 30, 31 are stitched in any approved way, their folds 30a, 31a straddling the base edge 1c of the main blank.

The assembly of the several component parts of the glove takes place in the following way:— With its outwardly flaring base portion, the body portion 1 of the glove forms a complete gauntlet, the side edges being stitched to each other. This disposes the V-shaped depression 4 on the palm side of the glove. The palm portion 10 is fitted to the body portion 1 with the edge of the tri-

angular projection 11 seating in and secured to the edge of the V-shaped depression 4. The edge marked a of the thumb tip backing 18 is secured to and throughout the edge marked b of the palm portion 10. The flap 12 is turned upwardly before the thumb backing is secured in place so as to provide an appropriate edge b substantially commensurate with the edge a. The edge c of the thumb upper portion 9 is secured to the edge d of the face of the glove. This projects the thumb upper portion 9 wholly free of the body portion 1 beyond the secured edge c. The thumb tip backing 18 is also wholly free of the palm portion 10 except throughout the secured edge a.

The thumb upper portion 9 is then secured to the palm portion 10 with the straight edges e and f of these respective parts together and the edges g and h together. As the completed thumb part must stand out from and be flexibly movable with respect to the body of the glove, and as the edges a and c are secured to the glove back and glove face, it is apparent that a fair amount of flexibility of the thumb stall is permitted by the slit 19, for in this way the upper portion 18 of the thumb stall is movably free from its lower portion 21 which is secured to the glove palm portion and glove body.

As this freedom, however, provides a gap of triangular form in the thumb stall, this gap is closed by the flap 12 of the palm portion 10 which has been turned up and which now accurately fits, with its outer edge i secured to that portion of the edge g which is below the edge h when the edges are secured together and the inner edge j of the flap 12 being secured to the relatively inner edge k of the division formed by the slit 19. This completes the assembly insofar as the parts 1, 2, 3 and 4 are concerned and provides a construction in which the thumb stall is permitted freedom and an outstanding natural position to avoid undue strain in applying or removing the glove.

What I claim is:

1. As a new article of manufacture, a glove including a hand back portion including four digit portions and a complete gauntlet portion, the latter being formed in its upper edge with a V-shaped depression, a palm portion including four digit portions secured to the digit portions of the hand back portion to complete the finger stalls, the palm portion terminating at its lower edge with a V-shaped extension fitting within and secured to the V-shaped depression in the gauntlet of the hand back portion, the palm portion being provided in line with the first digit portion with an inset curved edge and a flap divided from said edge and extending rearwardly from and in alignment with the initial digit portion, a thumb face piece having an edge secured to the curved edge of the palm portion, and a division to separate the upper and lower portions of the thumb face piece, a thumb back portion secured to the glove back throughout a curved edge of both such parts, the thumb back and thumb face being secured together throughout the remaining portions of their edges except for the line of division in the thumb face, the flap of the palm portion having an outline corresponding with and secured to one edge of the line of division of the thumb face portion and an otherwise unsecured edge portion of the thumb back.

2. As an article of manufacture, a glove made up of a glove back portion, a palm portion, an independent thumb face portion and thumb back portion, the thumb back portion being secured in

part to the glove back, the thumb piece being secured in part to the palm portion, the thumb back and thumb face being secured together throughout their otherwise free marginal edges except 5 for a free edge extending inwardly of the thumb face and a correspondingly curved edge portion on the thumb back, the palm portion of the glove

having a flap integral with such portion, said flap coinciding with the contour of and being secured to the edges of the thumb face and thumb back formed by the edge of the division on the thumb face and the corresponding curved portion of the thumb back.
